UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

LIFTER FOR FLAME-SPREADERS AND WICK-STOPS.

1,306,101.

Specification of Letters Patent. Patented June 10, 1919.

Application filed September 7, 1915. Serial No. 49,406.

To all whom it may concern:

Be it known that I, LEE S. CHADWICK, a citizen of the United States, residing at East Cleveland, in the county of Cuyahoga and State of Ohio, have invented a certain new and useful Improvement in Lifters for Flame-Spreaders and Wick-Stops, of which the following is a full, clear, and exact description, reference being had to the accompanying drawings.

This invention relates generally to oil or vapor burners and more particularly to a novel construction of wick stop together with means for lifting the flame spreader.

One object of the invention is to provide a wick stop in connection with the wick raising spindle whereby the raising of the wick will be automatically stopped when the spindle reaches a definite position.

Another object of the invention is to provide a wick stop of this nature which can be quickly and easily adjusted so as to compensate for the consumption of the wick.

Another object of the invention is to provide for the quick and easy elevation of the flame spreader so that the wick which has previously been raised to the proper position can be quickly and easily lighted before the same has reached its final or stopped position.

With these and certain other objects in view the invention consists in the novel features of construction and combination hereinafter described and pointed out in the claims.

In the drawings forming a part of this specification Figure 1 is a sectional view of an oil burner constructed in accordance with my invention, the elevated position of the flame spreader being indicated in dotted lines; Fig. 2 is a detail sectional view on the line 2—2 of Fig. 1; and Fig. 3 is a detailed perspective view showing the lower end of the lifting rod and guide for the same.

In carrying my invention into effect I employ a wick holder comprising the inner wick tube 10 and the outer wick tube 11 which are united as usual at their lower ends and receive therebetween the wick 12 which is incased in the perforated metal case 13 which is engaged by the wick raising wheel 14 carried upon the end of the spindle 15 which works through the tube 16 attached to

the outer wick tube in the usual manner. Near the outer end of this tube 16 is a sheet metal disk 17. This disk has a depressed central portion 18, raised annular shoulder 19, an outwardly extending flange 20, and at one point an oblique stop shoulder 21 unites the shoulder 19 and flange 20 serving to limit the rotary movement of the wick raising spindle as hereinafter explained.

The spindle 15 passes upwardly through the projecting portion of the sleeve 16 and upon its outer end is provided with an operating wheel 22 by means of which the wick raising spindle is operated. Upon the projecting portion of the sleeve 16 between the disk 17 and hand wheel 22 I arrange a wick stop 23 consisting of a strip of metal bent essentially U shape, the parallel members 24 being positioned upon the projecting portion of the sleeve, the upper end 25 being serrated to engage the serrated edge 26 of the wheel 22, and the lower end of this U shaped member is bent over the shoulder 19 and then provided with an angled foot 27 which is adapted to be projected through a similarly shaped opening 28 punched in the flange 20 adjacent to the stop shoulder 21, and when this foot piece 27 is pushed down into the opening 28 the serrated end 25 is disengaged from the serrated flange 26 of the hand wheel 22 and the wick can then be raised as desired. After the wick has once been raised to the proper position the U shaped stop member 23 is released and the spring 29 surrounding the sleeve in the dished portion of the disk will serve to project the said U shaped stop device out into engagement with the wheel 22. This brings the wick raising spindle and wick stopping device into locked engagement and the wick can be turned down for the purpose of extinguishing the same but when moved up it will be impossible to move the wick higher than the proper position inasmuch as the stop device in locked relation with the actuating wheel will engage the stop shoulder 21 upon the fixed disk 17.

When the edge of the wick has been consumed and it is desired to move the same up slightly, the foot piece of the stop device is pressed through the opening in the disk so as to disengage the hand wheel 22 which can then be turned so as to bring the wick up to

100

105

the proper position and then by releasing the stop device the spring immediately throws it into engagement with the operating wheel.

It will thus be seen that I provide an exceedingly simple and highly efficient wick stop in connection with the wick raising spindle thereby rendering it impossible to move the wick beyond the predetermined adjusted position and at the same time eliminating the use of radially extending arms which have heretofore been projected across the line of travel of the wick for the purpose of stopping the same.

In connection with my novel form of wick stop I employ a novel form of lifter for the flame spreader the purpose of which is to quickly and easily elevate the flame spreader the proper distance after the wick has been brought up to the proper lighting position and in this connection I would state that in practice I prefer to indicate upon the flange 20 a lighting point 30 to which the foot piece can be moved and which is so positioned with reference to the stop shoulder 25 as to place the wick in the most advantageous position for lighting.

The flame spreader may be of any suitable or desired construction and herein I have illustrated one consisting of the top 31, cone body 32, flange 33, and spreader body 34 the top carrying a thimble 35 at its upper end which is constructed with a recess 36 the lower inner edges of which are rounded or tapered as shown at 37 in order to provide 35 an opening somewhat larger than the main portion of the recess. The flame spreader normally rests upon the upper spanner 38 positioned in the inner wick tube and passing upwardly through the spanner and 40 through the flame spreader is the lifting rod 40 the upper end thereof fitting into the recess 36 of the thimble 35. This lifting rod 40 passes through an apertured strap 39 secured within the inner tube adjacent the 45 lower end thereof, and provided with an integral downwardly extending portion 41 longitudinally slotted as shown at 42. The rod 40 after passing through the guiding strip 39 is angled as shown at 43 to escape 50 the oil pipe 44 and is then projected outwardly as shown at 45 in order to pass through the slot 42. This rod is preferably swaged so as to provide the laterally projecting fins or ribs 46 which engage the rear 55 side of the depending portion 41 and cause the lifting rod to travel in a straight line through the strap 39 and central spanner 38. The outer end of the lifting rod is curved to provide a suitable handle and when this 60 end is moved upwardly as shown in dotted lines the lifting rod is moved vertically carrying the flame spreader up sufficiently to expose the end of wick so that the lighting operation can be quickly and easily accomplished and the thimble is so shaped with

reference to the upper end of lifting rod that the spreader will have a limited rocking movement thereon thereby facilitating the lighting operation as the flame spreader can be slightly tilted if desired to provide additional room for lighting.

It will of course be understood that the moment the lifting rod is released the flame spreader will descend to its normal or usual position and will be guided to such position 75 by the movement of the rod through the central spanner, apertured strap and vertically slotted guide.

A lifting device of the character described is highly desirable in connection with the 80 wick stop mechanism hereinbefore referred to. It will thus be seen that I provide a simple and efficient construction of wick stop and flame spreader lifter capable of connection to oil or vapor burners of the type now 85 in use.

Having thus described my invention, what I claim is:

1. In an oil burner, the combination with a wick holder and a wick therein, of an 90 elongated tubular bearing attached to said holder, a spindle in said tube having at one end means for engaging the wick and at the other end a serrated hand wheel, a disk carried by said tubular bearing and spaced 95 from said wheel, a locking member carried by said bearing and having one end in engagement with the serrations on said wheel and a spring interposed between said member and the disk, said disk having a stop in 100 the path of the locking member and also a latch for holding said member out of engagement with the serrations against the tension of the spring.

2. In an oil burner, the combination with 105 a wick holder and a wick therein, of an elongated tubular bearing attached to said holder, a spindle in said tube having at one end means for engaging the wick and at the other end a hand wheel, a disk carried by 110 said tubular bearing spaced from said wheel, said disk having a depressed central portion, raised annular shoulder, an outwardly projecting flange and a stop shoulder, said flange having an aperture adjacent said stop 115 shoulder, a locking member carried by the bearing and having one end in engagement with the hand wheel, the opposite end of said locking member being shaped to extend over the annular disk of the shoulder and 120 provided with an angled foot adapted to be projected through the opening in the flange or disk and a spring interposed between the locking member and disk.

3. In an oil burner, the combination with 125 a wick holder and a wick therein, of an elongated tubular bearing attached to said holder, a spindle in said tube having at one end means for engaging the wick and at the other end a hand wheel, a disk carried by 130

said tubular bearing and spaced from said wheel, said disk having a stop shoulder and an opening therein adjacent said stop shoulder, a locking member carried by said bearing and having one end adapted for engagement with the hand wheel, the other end being adapted to engage the stop shoulder and also of a size and shape to be projected through the opening in the disk, and a spring interposed between the locking member and disk.

In testimony whereof, I hereunto affix my signature.

LEE S. CHADWICK.
